UNITED STATES PATENT OFFICE.

FELIX DUENKEL, OF CHICAGO, ILLINOIS, ASSIGNOR TO WESTERN ELECTRIC COMPANY, OF CHICAGO, ILLINOIS, A CORPORATION OF ILLINOIS.

CARRIER FOR BRAIDING-MACHINES.

No. 856,946.

Specification of Letters Patent.

Patented June 11, 1907.

Application filed July 12, 1906. Serial No. 325,796.

To all whom it may concern:

Be it known that I, FELIX DUENKEL, a citizen of the United States, residing at Chicago, in the county of Cook and State of Illinois, have invented a certain new and useful Improvement in Carriers for Braiding-Machines, of which the following is a full, clear, concise, and exact description.

My invention relates to a spool-carrier for braiding machines, and its object is to simplify the construction of the carrier and to provide a device which will run at a greatly increased speed, and at the same time will decrease the wear by lessening the tendency of the flange of the carrier to cramp in the raceway of the machine.

In carriers of well known construction the slack in the thread is taken up solely by a weight provided for this purpose. In my invention the weight of the cop-holder and the material carried thereby is also utilized for controlling the slack, thereby greatly increasing the slack-controlling weight without any increase in the total weight of the carrier.

In the devices prior to my invention the weight of the cop-holder and the material thereon did not serve any useful function, but on the contrary rendered the carrier top-heavy and, owing to the centrifugal force due to the rapid movements of the carrier, rendered the guide flange of the carrier liable to be cramped in the guideway of the machine with which it was used. Such dead weight of the cop-carrier necessarily keeps down the speed of the machine.

From experience I have found that carriers of my invention are capable of operation at a speed of approximately 300 revolutions per minute, where old types of carriers are capable of operation at a speed of only about 200 revolutions per minute.

My invention may be more readily understood by reference to the accompanying drawings, in which,

Figure 1 is a side elevation of a spool-carrier embodying my invention, showing the cop-holder in its elevated position; Fig. 2 is a vertical section, with parts in elevation, showing the cop-holding sleeve in its lowered position; Fig. 3 is a detailed view of one of the parts.

Similar letters of reference are used to designate similar parts wherever shown.

The foot 1 of the spool-carrier is provided

with the usual guiding flange 2 extending beneath the same. A spindle 3 and a standard 4 extend vertically from the foot 1 and are preferably cast integral therewith.

A sleeve or cop-holder 5 is rotatably mounted on the spindle 3, said sleeve being adapted to hold a cop of thread 6 in the usual manner. The lower end of the sleeve 5 is provided with a series of radially projecting lugs 7, adapted to engage a flange 8 on the foot, and thus act as a stop for preventing the rotation of said cop-holder. The sleeve 5, however, has a longitudinal movement on the spindle 3, and the lugs 7 may be raised out of engagement with the flange 8 to permit the rotation of the sleeve, as shown in Fig. 1. A washer 9 upon the end of the spindle 3 limits the upward movement of said sleeve.

A weight 10 is slidably mounted upon the standard 4, said weight and standard being of the usual well-known construction. A slideable rod 11 has a loop 12 at its upper end which engages the standard 4 above the weight 10 and in the path of movement thereof. The lower end of said rod is provided with a foot 13 which straddles the flange 8, said foot extending beneath the sleeve 5. The weight 10 in its extreme upward movement thus engages the rod 11, lifting the same, which in turn lifts the sleeve 5. The upward movement of the rod 11 is limited by a screw or other stop 14 which engages with the foot 13. The upward movement of said rod is sufficient to lift the sleeve 5 until the studs 7 are out of engagement with the flange 8, and the sleeve, therefore, is free to rotate.

The thread is led from the cop 6 through a hole 15 in the standard 4, through the weight 10 and out through a hole 16 in the top of the standard. The weight 10 is thus supported in a bight formed in the thread between holes 15 and 16, and tends to take up the slack in the thread as the carrier moves in and out in braiding. As is apparent, when the sleeve 5 is lifted its weight supplements the weight 10, as a slack-controlling weight.

When there is the proper length of thread to allow the carrier to move in and out in braiding, the weight upon the thread will take up the slack and hold the thread at a proper tension. Under these conditions the studs 7 will engage the flange 8 and hold the

sleeve from turning. When more thread is required the tension of the thread will raise the weight 10, which will lift the rod 11, thereby also lifting sleeve 5 sufficient to permit its rotation to let off more thread.

Under normal operation of the braiding machine the weight 10 is pressing against the rod 11, slightly lifting the same and thus utilizing the weight of the sleeve 5 and the cop 6 as an additional slack-controlling weight.

Having described my invention, I claim:

1. The combination with a cop-holder, of means whereby said holder acts as a weight 15 for taking up slack in the thread fed from said cop.

2. In a spool-carrier, the combination with a spindle, of a sleeve rotatably mounted thereon and adapted to hold a cop of thread, 20 and means whereby said sleeve and cop act as a weight for taking up slack in the thread fed from said cop.

3. The combination with a cop-holder, of a weight for taking up slack formed in the 25 thread fed from the cop, and means whereby the weight of said cop-holder supplements the slack-controlling weight.

4. A spool-carrier comprising a foot having a vertically extending spindle, a sleeve 30 rotatably mounted on said spindle and adapted to hold a cop of thread, said sleeve having a longitudinal movement on said spindle, a stop for preventing the rotation of

said sleeve when in its lowered position, a 35 slidably mounted weight for taking up slack in the thread, and a slideable rod extending above said weight and beneath said sleeve in the paths of movement thereof.

5. In a spool-carrier, the combination with a spindle, of a sleeve rotatably mounted 40 thereon and adapted to hold a cop of thread, said sleeve being also mounted to have a vertical movement on the spindle, a stop for preventing the rotation of said sleeve when in its lowered position, and means whereby 45 the tension of the thread raises the sleeve free from said stop.

6. A spool-carrier comprising a foot having a standard and a spindle, a sleeve rotatably mounted on said spindle and adapted 50 to hold a cop of thread, said sleeve having a vertical movement on said spindle, studs on said spindle, a flange or stop with which said studs are adapted to engage when the sleeve is in its lowered position on the 55 spindle, a weight slidably mounted upon the standard, and a rod slidably engaging said standard in the path of movement of said weight and extending beneath said sleeve for lifting the same free from said stop. 60

In witness whereof, I, hereunto subscribe my name this 9th day of July, A. D. 1906.

FELIX DUENKEL.
